(57) **CLAIM**

The ornamental design for a manual personal electronic device power charger, as shown and described.

DESCRIPTION

FIG. 1 is a right elevation view of a manual personal electronic device power charger showing my new design;
FIG. 2 is a left elevation view thereof;
FIG. 3 is a front elevation view thereof;
FIG. 4 is a rear elevation view thereof;
FIG. 5 is a top plan view thereof;
FIG. 6 is a bottom plan view thereof; and,
FIG. 7 is an isometric view thereof, shown in environmental use.
The broken lines shown represent unclaimed subject matter and form no part of the claimed design.
